DESIGN FOR A SPRAYER

Horace L. Weeks, Lowell, Mich., assignor to H. D. Hudson Manufacturing Company, Chicago, Ill., a corporation of Minnesota

Application November 18, 1940, Serial No. 96,645

Term of patent 14 years

To all whom it may concern:

Be it known that I, Horace L. Weeks, a citizen of the United States, residing at Lowell, Kent County, Michigan, have invented a new, original, and ornamental Design for Sprayers, of which the following is a specification, reference being had to the accompanying drawing, forming part thereof, and in which

container and a portion of the gun broken away for convenience of illustration; and

Figure 3 is a fragmentary end elevational view thereof with a portion of the container broken away, and the handle omitted, for convenience of illustration.

The dominant features of the design reside in the portions shown in full lines.

I claim:

The ornamental design for a sprayer substantially as shown and described.

HORACE L. WEEKS.
